CLAIM

The ornamental design for a chain link for a conveyor chain, as shown.

DESCRIPTION

FIG. 1 is a perspective view of a chain link for a conveyor chain showing our new design;

FIG. 2 is a side elevational view thereof;

FIG. 3 is a top plan view thereof;

FIG. 4 is a bottom plan view thereof;

FIG. 5 is a rear elevational view thereof;

FIG. 6 is a front elevational view thereof.
